UNITED STATES PATENT OFFICE.

EDWARD M. BUCKIUS, OF LOS ANGELES, CALIFORNIA.

COLLAPSING TAP.

No. 832,716.

Specification of Letters Patent.

Patented Oct. 9, 1906.

Application filed December 11, 1903. Serial No. 184,792.

To all whom it may concern:

Be it known that I, EDWARD M. BUCKIUS, a citizen of the United States, residing at Los Angeles, in the county of Los Angeles and State of California, have invented a new and useful Collapsing Tap, of which the following is a specification.

An important object of this invention is to provide a tap that will expand and hold the dies or chasers evenly and firmly and after it has performed its work may be quickly and readily collapsed to enable it to be withdrawn.

A further object of the invention is to provide improved means whereby the collapse of the tap may be effected automatically when the tap has reached the desired depth, and in this connection my invention provides for adjustment of the depth at which this action shall take place.

Another important object of my invention is to provide for reaming or undercutting the hole in advance of or below the tap-dies so as to clear the scale and bring the hole to exact size for operation of the tap-dies without the use of separate tools for that purpose.

An object of the invention is to provide a running tap with which to cut threads in pipe-elbows and other fittings where the screw-threads are required to extend as close as possible to the end of the way into which the tool must be inserted while cutting the thread. I accomplish this object by providing a tap having a cutter and a chaser, the chaser being located rearwardly of the cutter both axially and circumferentially of the tap and terminating approximately in a plane in which the cutter extends and which cuts the tap at right angles to its axis.

In the practical form I deem preferable the back of the cutter is practically in the plane of the front of the chaser, the terms "back" and "front" being here used with reference to the axial movement of the tap in the act of cutting, and the front of the cutter is brought as close to the front end of the tap as the strength of the material will admit.

Owing to the hard scale in pipe-fittings and other rough castings the life of the dies or chasers ordinarily used for tapping the same will be greatly prolonged by reaming the hole in advance of the chasers. This invention enables such reaming to be accomplished at the same operation with the tapping of a hole in an elbow or elsewhere practically to the end of the hole.

Another object is to provide a simple construction of means for catching and releasing the collapsing mechanism. This I do by providing a sliding catch on the outside of the body of the tap, the same being mounted thereon by means of a sleeve and arranged to engage a handle which projects outward from the barrel which has the cams that move the chasers.

Other features and objects of the invention will appear in and from the following description and claims.

The accompanying drawings illustrate the invention.

Figure I is a plan of the tap with the shank in section. Fig. II is a side elevation thereof with the dies or chasers expanded. Fig. III is a section on the line III III in Fig. IV with the parts in collapsed position, only one of the dies or chasers being shown. Fig. IV is a section on the line IV IV in Fig. I. Fig. V is a detail elevation of the die-operating barrel. Fig. VI is a plan of the bottom plate of the tool. Fig. VII is a section on the line VII VII in Fig. II. Fig. VIII is a section on line VIII VIII in Fig. IV. Fig. IX is an elevation at right angles to Fig. II, showing the dies or chasers in retracted position. Fig. X is a plan of the spring device for effecting collapse of the tap. Fig. XI is a perspective view of one of the dies or chasers. Fig. XII is a fragmental section on the line XII XII in Fig. VI.

1 designates the shank or spindle of the tap, and 2 the body or die-holding member thereof, which is desirably cylindrical and is fastened or screwed to the shank in the usual manner. Any desired number of radial slots or channels 3, formed in the lower end of this body 2, serve to receive the dies or chasers 4, which are slideable in said slots and project at their inner ends into a cylindrical chamber or recess 5 in the lower part of the member 2, said chamber containing the various operating parts for the dies or chasers. A plate or disk 6, secured by screws 7 and pins 35 to the bottom of member 2, serves to close the lower end of slots 3 and recess 5 and also serves to carry the reaming, sizing, or clearing cutters 8. Said cutters are seated in radial slots 9 in plate 6, and screws 10, working in the plate and engaging with the inner ends of said cutters, serve to adjust the radial projection of same, clamp-screws 11 serving to hold the cutters firmly in position when adjusted.

The end plate 6 has on its front face a re-

- cess 62, from which the holes for screws 10 extend radially outwardly, so that the heads of said screws are accessible through the recess 62 from the end of the tool. By mounting the cutters and their adjusting means in the plate facility of construction is secured, and by the removal of the plate the cutters and their adjusting means are removed and access is given to the interior of the tool.
- 10 When the screws 11 are tightened, the backs of the cutters are forced against the front end of the body 2, and thus held in the plane in which the fronts of the chasers terminate, so that as the tap is advanced and rotated each 15 chaser practically cuts at once in the path cleared by its preceding cutter, and thus it is made possible to tap a hole closer to the bottom than possible with any reaming-tap heretofore known.
- 20 By making the cutters independently adjustable and providing independent adjusting means for each cutter it is made possible to keep the tool true regardless of the uneven wear of the cutters, and it is made possible to 25 withdraw and replace any cutter by simply loosening the binding-screw 11 and without changing the adjustment of any other cutter. With this independent arrangement of cutters a tap adapted for a plurality of cutters 30 may be used with its full complement or any less number of cutters with equal facility. I prefer to use three or more cutters, depending on the diameter of the tool, in order to equalize the strain.
- 35 Another advantage arising from the use of independent cutters is the ease with which any cutter may be removed or replaced at any time without disturbing the others or requiring an entirely new tool, as the case of 40 breakage.
- The inner face of the plate 6 is provided with projections 6', preferably segmental, between which are formed radial grooves 3'. The grooves 3' register with the grooves 3 in 45 the body 2 and receive the lower ends of the dies 4. This causes the dies to bear most of the rotative strain that is placed upon the plate by the cutters 8, and thereby makes a strong construction with comparatively light 50 material. The projections also extend up into the cavity or recess of the body 2 of the tool, as shown in Fig. XII, and thereby centers the plate, so that the cutters 8 travel in a true circle concentric with the circle traveled 55 by the chasers 4. They also increase the amount of stock at the points where the screws 10 pass through, thereby increasing the strength where it would otherwise be weakened by the screw-hole.
- 60 The radial grooves 9 are made in the top of plate 6, so that when the plate is secured in position on the lower end of the body 2 by the screws 7 the tops of the cutters are substantially on a line with the lower ends of the 65 chasers 4, so that the chasers follow immedi-

ately at the rear of the cutters, and thereby permit of their passing entirely through the opening made by the cutters without obstruction, as in an elbow or other construction, which would not permit of the use of 70 cutters so far in advance of the taps as is necessary where they are arranged longitudinally of the tool instead of radially.

Another advantage arising from the use of such a plate is the ease with which the adjustment of the cutters can be effected from the bottom of the tool, as all that is necessary is to adjust each cutter by means of its screw 10 and then tighten it against the lower end of the body 2 by its screw 11. In case of break- 75 age the broken cutter can be taken out by loosening its screw 11, which will also permit of the insertion of the new cutter, which can then be adjusted by its screw 10 and fastened by the screw 11, and if it be desired to use the 80 tool as a cutter only all that is necessary is to retract the chasers and leave the cutters projecting the required distance, or the cutters may be removed or a plane plate substituted for the plate 6 and the tool used as a tap by 85 projecting the chasers 4.

12 designates an operating barrel or cylinder rotatable on a shaft or centering means 13. This barrel comprises a die-expanding cam hub or collar 14, a die-collapsing cam-plate 15, and an operating-collar 16, all fastened together and to shaft 13, so as to move as a single unit, the collar 16 fitting and turning within the sleeve-recess 5 of the tap-body. Collar 16 is provided with a hole or seat for 90 an operating-handle 17, whereby the barrel may be turned. Cam-faces 18 on the collar 14 engage with the inner edges of dies 4 when the barrel is turned by handle 17 in the direction opposite to the arrow in Fig. III to 95 force the dies outwardly, these edges being beveled to give a better bearing for this purpose. Cam device 15 has cam-slots 19 engaging pins 20 on lugs 21, extending upwardly from the respective dies 4, so that 100 when the barrel 12 is turned in the direction of the arrow in Figs. III and VIII the dies will be drawn inwardly or collapsed. Such movement of the barrel is effected by a 105 spring 22, connected at one end to collar 16 110 and at the other end to the body 2 of the tap.

A shouldered collar or sleeve 23 surrounds the body 2 of the tap and may be adjusted circumferentially or angularly around the same, being clamped in desired position by 115 clamp-screws 24, working in slots 25 in said collar. Handle 17 passes through a slot or notch 26 on the sleeve 23. When moved in one direction, the handle 17 engages with a locking device consisting of a slide 27, movable vertically in a guide or way 28, formed by the shoulders of the sleeve, and having a catch or seat 29, adapted to engage over and catch the handle, this slide falling into catching position by gravity. A tappet-block or 120

controlling device 30 is connected to and 5 slideable vertically on the slide 27, being adjustable thereon by a screw 31, so as to vary the longitudinal position of a roller 32 on the lower end of said block, which is adapted to engage the work or part being operated upon to raise the slide relatively to the tap-body and withdraw the catch thereon from the handle 17, and the barrel 12 springs back under the influence of spring 22, thereby collapsing the dies through the action of cam-slots 19. Screw 38 on block 30, working between stops 39 39, fixed on sleeve 23, limits the movement of the locking device and prevents the slide 27 from coming out of the way 28.

The cam-faces 18 give an even bearing substantially from top to bottom of the tap-dies, as distinguished from the liability to uneven or partial support given by wedges or plugs.

By adjusting the circumferential position of collar 23 the effective stroke of handle 17 is limited so as to stop the cam at the proper 25 point to give the desired expansion of the dies.

An annular oil-channel 36 is provided in the top of the body portion 2 of the tool, and ducts 37 lead therefrom downwardly and 30 then outwardly to discharge oil directly over the dies. Dies 4 are removable, slots 33 being made in the cam-hub 14 to enable insertion of lugs 21 and pins 20 into engagement with cam device 15.

To permit of the rotary movement of the barrel without interfering with the lugs 21, the barrel is recessed circumferentially or 35 provided with a space between the cam device 15 and the hub 14, within which the lugs 40 are seated as soon as the barrel is rotated. The lugs 21 are inserted into the recesses 33 and the pins 20 into the slots 19 as the blades or chasers 4 are inserted into the deepest portions of the longitudinal recesses forming the 45 cam-faces 18, after which the chasers are moved up so that the lugs are in the plane of the circumferential recess, where they are held by the plate 6 at the lower end of the body. The depth of the recesses 33 is just 50 sufficient to permit of the insertion of the lugs without having the pins engage with the lower surface of the cam-plate 15.

In operation the sleeve 23 is adjusted to the proper position for the desired cut of the 55 tap-dies, and the controlling device 30 is adjusted according to the distance it is desired to tap into the hole. The undercutters or reamers 8 are also adjusted to cut the hole to the proper size for the action of the tapping-dies. Handle 17 being turned until it engages with the catch 29, the cam-faces on collar 14 force out the dies to the proper extent. Then the tool is entered in the hole, and on being rotated its collars 8 first clean the hole 60 of scale and bring it to proper size, and the

tapping-dies then cut the threads. When the hole has been tapped to the proper depth, the controlling device 30, as above described, releases the locking-catch 29 and allows the working barrel to be moved back automatically by action of spring 22, the cam-plate 15 causing the dies to be drawn in or collapsed, enabling the withdrawal of the tool. 70

The construction above described may be variously modified without departing from the spirit of my invention. For example, the various parts of the working barrel may be rigidly connected in any suitable manner, as by being formed in one integral piece. 75

What I claim, and desire to secure by Letters Patent of the United States, is— 80

1. In a collapsing tap, a recessed and longitudinally-slotted body, a circumferentially-recessed barrel rotatably mounted in the body, the portion of the barrel on one side of said recess being provided with cam-slots, and the portion on the other side being provided with recessed cam-faces, chasers mounted in the slots of the body and engaged by said cam-faces, an extension carried by each 85 of said chasers for fitting in one of said cam-slots, and a plate at the end of the body.

2. The combination of a tap-body, dies carried thereby, a barrel rotatable within the tap-body and having cam portions engaging 95 said dies, operating means connected to the barrel, a member movable around the tap-body and angularly adjustable thereon, a slide mounted on the said member and having a catch portion to engage the operating 100 means aforesaid, a trip device movably mounted on said slide, a screw on the slide engaging the trip device for adjustment thereof longitudinally of the tap-body, and a spring for rotating the barrel. 105

3. A collapsing tap comprising a body provided with radially-movable chasers, means for moving the chasers, a grooved plate at the end of body, cutters in said grooves, and means carried by the plate for 110 adjusting the cutters.

4. In a collapsing tap, a body provided with radially-movable chasers, means for moving the chasers, a plate at the end of the body provided with radial grooves in the surface adjacent to said body, and with projections extending into the body and engaging the chasers, a cutter in each groove, means for adjusting the cutters longitudinally, and means for clamping them against the end of 115 the body. 120

5. In a collapsing tap, a body provided with radially-movable chasers, means for moving the chasers, a plate on one end of the body, one surface of which is recessed and the 125 opposite surface is grooved radially and is engaged with the chasers, the portions of the plate at the bottom and at the inner end of each groove being each provided with a screw-threaded hole opening into the recess, a cut- 130

ter in each groove, and a screw in each of said openings for engaging with and adjusting the cutters.

6. In a collapsing tap, a recessed body provided with radially-movable chasers, means for moving the chasers, a plate at the end of the body provided with projections for fitting in the recess of the body for centering the plate, and radially-arranged cutters adjustably mounted in the plate.

7. In a collapsing tap, a recessed and longitudinally-slotted body, a plate at one end of the body, one face of which is provided with segmental projections for fitting in said recess and centering the plate, said projections being spaced apart to form grooves to register with the slots in the body, radially-movable chasers in said slots, one end of each of which fits in its respective groove in the plate, and means for moving the chasers.

8. In a collapsing tap, a recessed and longitudinally-slotted body, a circumferentially-recessed barrel rotatably mounted in the body, the portion of the barrel on one side of said recess being provided with cam-slots and the portion on the other side being provided with recessed cam-faces, chasers mounted in the slots of the body and engaged by said cam-faces, one end of each of which chasers is provided with a lug, a pin on each lug for fitting in one of said cam-slots, and a plate at the end of the body.

9. In a collapsing tap, a body, radially-movable chasers mounted therein, a rotatable member for moving the chasers, a handle projecting from said member, a shouldered sleeve rotatably mounted on the body, means for adjustably locking the sleeve against rota-

tion, a shouldered catch on the sleeve for engaging the handle, means for automatically releasing the catch from the handle, and means for returning the member to its normal position.

10. In a collapsing tap, a body, radially-movable chasers mounted therein, a spring-actuated rotatable member for moving the chasers, a handle projecting from said member, a shouldered sleeve rotatably mounted on the body, means for adjustably locking the sleeve against rotation, a guideway on the sleeve, a longitudinally-movable slide on said way provided with a notched portion for engaging with the handle, and means for automatically releasing the slide from the handle.

11. In a collapsing tap, a body, radially-movable chasers mounted therein, a rotatable member for moving the chasers, a spring-actuated handle projecting from said member, a recessed sleeve rotatably mounted on the body, means for adjustably locking the sleeve against rotation, a longitudinally-movable notched slide for engaging with the handle, a tappet on the slide, means for limiting the movement of the tappet, and means for moving the slide to release the handle at any desired predetermined point.

In testimony whereof I have signed my name to this specification, in the presence of two subscribing witnesses, at Los Angeles, in the county of Los Angeles and State of California, this 4th day of December, 1903.

EDWARD M. BUCKIUS.
